PROCESS FOR TREATING HYDROCARBON VAPORS

Willis F. Sims and Venus U. Cloer, Wichita Falls, Tex., assignors to Panhandle Refining Company, Wichita Falls, Tex., a corporation of Texas

Application February 16, 1928. Serial No. 254,753

6 Claims. (Cl. 196—61)

Our invention relates to the treatment of hydrocarbon oils, and more especially to such treatment for the purpose of reducing higher boiling compounds to lower boiling compounds, commonly called cracking. The invention has for its object the production of an improved process of cracking, and we attain this object by treating hydrocarbon vapors, which may be vapors from petroleum products, vapors from coal tar products, vapors from shale oil products, etc., with heat and under subatmospheric pressure in such a manner that the higher boiling constituents are broken down to lower boiling compounds similar to gasoline or related light oils, and recovering the gasoline-like material and related light oils so produced.

Very briefly stated, according to this invention, the oil to be treated is first heated under pressure (which may vary from 15 to 60 lbs. or even higher according to the character and grade of the oil being treated), until sufficient thermal energy is accumulated for vaporization of heavy fractions, is then released into a flashpot positively maintained under subatmospheric pressure wherein it flashes into vapors, is then passed through an open connection to a cracking still, which may be a pipe still of approved construction, which is also under subatmospheric pressure, preferably lower than that maintained on the flashpot, is then passed through fractionators or dephlegmators to a vapor outlet from which it goes to a cooler or condenser and separator. Two features are of importance, viz., the maintenance of subatmospheric pressure on the forwardly proceeding vapors in the flashing zone and in the cracking zone, whatever the form of apparatus may be, and the subsequent handling of the cracked vapors in such manner as to permit reflux distillate and make-up oil to be pumped back to the flashing zone through heat exchangers adapted to absorb heat from the cracked vapors.

We shall describe herein power actuated pumping means for positively maintaining the vacuum or subatmospheric pressure on the cracking still and the flashpot. Our invention includes the positive maintenance of this low pressure through these two stages or pieces of apparatus in every case, and according to the character of the oils being treated, upon other portions of the system. The suction or vacuum pumping means doing this work is piped so that it may be connected at will either with the vapor outlet of the separator or at a point between that and the cracking still. We shall claim this variable method of

connection herein, and we shall also claim the broad idea of positively maintaining subatmospheric pressure on the cracking still and on the flashpot, and the specific ideas of including the vacuum pump therefor directly between the cracking still or zone and the first fractionator, as well as on the output of the separator.

For a full understanding of our process, reference should be had to the accompanying drawings, in which

Fig. 1 is a diagrammatic representation, with parts in section, of the principal pieces of apparatus required to practice our invention.

Fig. 2 is a flow sheet showing the several steps in the course of the oil when the vacuum pump is hooked up on the cracking still and flashpot only, with its output going to the first fractionator.

Fig. 3 is a similar flow sheet showing the flow when vacuum is maintained on the entire plant through the terminal separating and receiving drum.

Referring to the drawings, and first to Fig. 1, the principal pieces of apparatus employed in the operation of our process are the preheater 57, the flashpot 1, the cracking still 56, the dephlegmators or fractionators 6—7—8, and the suction pump 14 connected between the pipes 30—40 and the pipes 39—42 whereby the pump may be connected either between the cracking still 56 and the first dephlegmator 6 or between the separator or receiving drum 10 and the absorption tower 11, which will be presently referred to. The pipes 30—40 and 39—42 are provided with valves 3, 4, 5, 46, 19, 20, 21 and 25. Each of the dephlegmating towers 6—7—8 contains in its top a heat exchanger 26, 27 or 28, whose superficial area and capacity is increased in the direction of flow by increasing the number of coils. It is to be observed that not only does the temperature become higher in the towers 8, 7 and 6 in that order, but the temperature and the boiling point of the vapors in each succeeding fractionator 6, 7 and 8 in that order become lower. The input of the first of these heat exchangers 28 is connected through the valved pipe 32 to the output of the pump 15, with valved branch 31 to the top of the absorbing tower 11, the flow from which is regulated by valve 35. From the output end of the heat exchanger 26, the pipe 22 extends to the flashpot 1 direct, without going to the preheater 57. Charging stock is fed into the preheater under pressure by the pump 54 and in order to build up pressure and accumulate thermal units in the coil 57, the valve

23 is provided which in operation is complementary to the valves 35 and 38. Means are provided to regulate the heating of the reflux fractions and the make-up oil in the heat exchangers 27-28. These are shown in the drawings as bypasses controlled by valve 36-37, which like the other valves described can be set at anything from closed to open.

10 The function of the pump 12 is to draw off the heavy precipitate or tarry matters from the bottom of tower 6; the function of pump 13 is to draw off heavy gas oil which is thrown down in the bottom of tower 7, and return the same in part through valve 18 to the middle section of tower 6 and in part through valve 47 to the heat exchanger 26 as reflux to be retreated. The function of pump 14 is to produce suction either directly through the valve 4 on the output of the cracking still 56, (and conversely to build up ahead of it through pipe 39 and valve 5 a constant positive pressure, that is to say a pressure at or above atmospheric in the towers 6-7); or through the valve 21 on the output 30 of the separator or receiving drum 10 and so through the entire system on the output of the cracking still 56. The function of the pump 15 is to withdraw light gas oil from the bottom of tower 8, drawing it through the heat exchanger 17 and discharging it either in whole or in part through the valved branch 31 into the upper part of absorption tower 11, or in whole or in part through the valved branch 32, into the heat exchangers 28-27-26, according to the settings of the valves 31 and 32. The portion discharged through the valve 31 into the tower 11 has for its function 35 the absorption of gasoline-like fractions which have become entrained with the fixed gases. The entrained gasoline-like material is stripped from these gases and absorbed by the oil entering the head of the tower through the valve 31. This tower as well as the towers 7-8 is a bubble tower, but it is to be understood that any preferred apparatus may be employed which will afford a large superficial area over which gases passing in 40 one direction and the oil passing in the other may come into contact.

45 The pipe 60 from the pump 15 is provided with a branch 34 through which make-up oil is supplied to the system. This make-up oil as its name indicates, is to supply in part or in whole, the losses due to conversion, condensation, and removal of portions of the oils from the system through the cooler 9 and the separator 10, or otherwise. Since this make-up oil may be in part used through the valve 31 as an absorbing agent 50 in the tower 11, for which purpose light gas oil is also drawn by pump 15 through the heat exchanger 17 from the bottom of tower 8, obviously the make-up oil to cover this purpose may be gas oil. In such case it may be assumed, as 55 will be understood by those skilled in this art, that the charging stock supplied from pump 54 is also gas oil. It will be also understood however by those skilled in the art that our method is by no means confined to gas oil nor to any particular variety of oil, but that the process is adjustable to any variety and all grades.

60 Referring now to Fig. 2, the pieces of apparatus used in our process are indicated by symbols and the flow of oil through the system will be clearly 65 apparent from the following statement of operation. In this figure the valves 4, 5, 19 and 46 are supposed to be open and the valves 3, 20 and 21 are supposed to be closed, so that the pump 70 75 14 is included directly between the output of the

cracking coil 56 and the input of the fractionator tower 6. In this position the pump maintains a subatmospheric pressure in the cracking coil and the flashpot, and an atmospheric or superatmospheric pressure on the vapors passing into the fractionator 6 and through the rest of the system.

80 Referring to Fig. 3, the same parts and the same operation are apparent, with the exception that instead of being connected directly between the cracking coil 56 and the first fractionator tower 6, as in Fig. 2, the pump 14 is shown disconnected from the circuit of Fig. 2 and connected between pipe 30 leading from the separator 10, and pipe 42 leading to the absorbing tower 11. With this connection it will be found that suction exists together with a subatmospheric pressure produced thereby all the way back from the pump 14 through the pipe 30 and the separator 10, through the cooler 9 and the fractionating towers 8, 7 and 6, through valves 5 and 3 which are now opened, (the valves 4 and 19 being understood to be closed and thereby eliminated) and through the cracking coil 56 and the open connection therefrom to the flashpot 1. 90 By these means the entire system is placed under subatmospheric pressure, and this specific mode of operation of the process will be claimed herein.

95 The operation of the system thus described is 105 as follows: charging stock is pumped into the primary heater 57 by pump 54 and is heated in the furnace 2a at first by burners 52b and afterward by heated gases and products of combustion from furnace 2, to a temperature of from 110 400° F. to 800° F. which is above the equilibrium boiling point at the subatmospheric pressure maintained in the flashpot, that is to a point higher than that required for vaporization of the grade of oil under treatment, or in other 115 words, the charging oil is heated under pressure. It is then admitted through valve 23 to the flashpot wherein it instantly passes into the vapor phase. The reduced pressure causes more of the hot oil, or superheated oil, entering the flashpot 120 to be vaporized than is possible at atmospheric pressure. It also reduces the tendency of the vapor to be condensed by the walls of the flashpot. That vapor which does condense will be a heavy residuum and is removed from the flashpot 1 through line 24, by a pump not shown in the drawings. In this vapor form the oil is drawn in a turbulent, rapidly moving body through the cracking coil 56 wherein it is heated to a temperature preferably from 1000° F. to 125 1200° F., and through the valved pipe 5 into the tower 6. In this tower the first separation takes place, the vapors as they rise meeting the gas oil from pump 13 entering the tower through valve 18 and also encountering the surfaces of the heat 130 exchanger 26. The result is a cooling and deposit of heavy fractions or a tarry asphaltic mixture which is removed from the system by the pump 12. The heavy gas oil admitted through the valve 18 dilutes this tarry mixture so as to prevent the deposit of any dried coke or tar in the 135 tower.

140 The vapors thus initially cleansed are at a temperature of from 650° F. to 720° F. and pass over the first gooseneck into the lower part of 145 the second tower 7 and rise up through the bubble pans and through the recticulations of the heat exchanger 27. There is thrown down in this tower (assuming the crude to be of average formula) heavy gas oil, which is drawn off by 150

the pump 13 and carried back to the tower 6 as above stated. That part of it which is not required for washing out the tar referred to, is passed upward by opening the valve 47 to the 5 heat exchanger 26 and thence through pipe 22 to the flashpot for retreatment. The contact of the vapors with the heavy gas oil over the bubble pans or their equivalent serves to strip absorbed light oils from the heavy gas oil before 10 it is drawn off. The vapors, having given up more heat through the heat exchanger 27, pass through the second gooseneck to the lower part of the third tower 8 through which they bubble up as before and in addition to the bubble pans, 15 they pass through the reticulations of the heat exchanger 28. The condensate in this case is a light gas oil, which is stripped of absorbed gasoline-like material or other light oils by the rising vapors, and the low boiling fractions remaining 20 as vapors or fixed gases go over through the top of the tower and the third gooseneck to the cooler 9 wherein condensable portions are condensed and pass to the separator 10. Valved pipe 29 leads from this separator 10 to storage, while 25 the pipe 30 goes to the pipe 42 and thence to tower 11, carrying the cooled fixed gases with entrained gasoline-like material. These gases are drawn out of the separator and storage tank 10 through the pipe 30 and valve 21 by the pump 30 14 (valve 25 being closed) and back through valve 20, and pipe 42, into the lower part of tower 11, as indicated by the arrows. In this tower as already stated make-up oil or light gas oil drawn from the bottom of tower 8 through 35 heat exchanger 17 is fed into the upper part of the tower 11 through the valve 31. The heat exchanger 17, it should be noted, must be of such a type and capacity, and so designed, as to cool the oil passing through it to the pump 15 40 so that it may be as near atmospheric temperature as possible, and to this end it may if necessary be supplemented by any known or suitable cooling device 17' (see Fig. 2). This oil, after passing through the valve 31 meets the uprising 45 fixed gases, absorbs the gasoline-like material carried thereby and carries the same down with it to the bottom of the tower 11 from whence it is drawn off by pump 16 and forced back through the heat exchanger 17 and the valve 33 into the tower 8. In passing from the tower 11 through the heat exchanger 17 and into the tower 8, the gas oil with the absorbed gasoline-like material becomes heated, and in the tower 8 the gasoline-like material vaporizes, rises, and goes over the gooseneck, being condensed in the 50 cooler 9 and passed through the separator 10 to the storage tank. The fixed gases in tower 11 pass out of the top thereof through the waste pipe 48.

60 By stripping the absorbing oil of its light gasoline-like content in the presence of the heavier vapors in tower 8, we get a product more stable under atmospheric conditions than is gasoline produced in the ordinary way and having the light strippings from the absorbing oil added to it afterwards. In other words, the absorbing tower 11 operating in connection with the tower 8, constitutes a stabilizing system which also takes advantage of the heat available in bottoms from tower 8, and uses the same to strip the absorbing oil of its light gasoline-like content.

70 It is obvious that it is possible to adjust the valve 35 and the valve 32 or the valves of the pump 54 typified at 23 so that the original charg-

ing stock and the make-up oil will be fed in in complementary quantities and so as to maintain equivalent average temperatures and pressures in the pipes 22 and 52 leading to the flashpot. The valves 23 and 38 materially assist in this adjustment, so as to produce uniform average temperature and pressure at the flashpot, whether the input is fresh charging stock, or whether it is reflux fractions drawn from the towers 7-8 by the pumps 13 and 15, or make-up oil entering the system through pipe 34.

75 It may be noted in passing that we use the words make-up oil for convenience as follows: make-up oil, or charging stock, are really one and the same thing; but in a cracking system of this kind there is a definite quantity of the charging stock which during operation is consumed or converted to gasoline-like material. As this conversion is effected, a quantity of the charging stock must obviously be added to the system to make up for that quantity which has been converted and taken from the system, hence our use of the term "make-up oil". We have used the words "light gas oil" in the description because in this case we assumed as a matter of consistency that the charging stock described was light gas oil. This point should be noted, that in addition to the make-up oil which enters through the pipe 34 there are also the reflux fractions from pumps 13 and 15 which pass up through the pipes 60 and 61. It is part of the invention in this case to abstract and use the heat taken from the vapors in the dephlegmators 6, 7 and 8 to preheat the reflux "make-up oil" which of course is charging stock, so that the preheater 57 may be shut down in 100 whole or in part. In starting the system on stream, it is necessary to charge the system from the pump 54 and to preheat the fresh charging stock in the preheating still 57. After a sufficiency of this oil is introduced and heated however, the 105 temperature of the vapors in the three towers 6, 7 and 8 will have been raised to preheating temperature and thereafter, "make-up oil" or "charging stock" is introduced through the pipe 34 and the valve 35 and is passed through the 110 heat exchangers 28-27-26 and the pipe 22 to the flashpot 1 as previously stated. It will now be understood that the only difference between charging oil introduced by pump 54 and by the pipe 34 and valve 35 lies in the fact that the 115 former has to be preheated while the system is cold and therefore goes to the flashpot through the preheater 57, while after heat has been developed and cracking and fractionating are proceeding, the charging stock or make-up oil is 120 heated and goes back to the flashpot through the 125 heat exchangers 28-27-26.

130 It is to be understood that the above apparatus is only one of the forms of apparatus that may be used to obtain light oils from hydrocarbon vapors by our process. The form of apparatus is governed largely by the nature of the vapor under treatment. Thus, we are not limited to any particular type of pump, because the piston type of pump will work equally as well as the rotary 135 pumps shown in these positions.

140 The apparatus described above when operated on vapors from petroleum gas oil of approximately 30° Baumé gravity, with a vacuum capable of holding up a 5-inch column of mercury 145 maintained on the system at the separation drum exit 30, gave a yield of 16 to 60 percent according to the character and grade of the crude, of light oils having a New Navy gasoline boiling range and 3 to 5 percent of absorbed light oils which 150

when separated resembled natural gasoline in its boiling range. This gasoline-like material is high in unsaturates and aromatics containing from 60 to 80 percent unsaturated compounds and from 5 to 10 to 25 percent of aromatic compounds, and is a very desirable motor fuel. More fully stated a typical run on the unit of apparatus described herein and according to our method gives the following results:

10 *Charging stock:*

Gas oil of 33.5° Bé. gravity derived as an intermediate product from our present Dubbs unit having an I. B. P. of 394° F. and an E. P. of 620° F.

15 *Time on stream:*

96 hours.

Having thus described in general the operation of our system, it may be remarked that by varying the combinations of valves, pumps, direct and reflux feed, it is possible to use the same apparatus in various ways and for different operations, with different classes of oils. The type of equipment used on our process will, of course, also vary with the kind of vapors under treatment. The equipment shown in our drawings is that used when operating on vapors produced from 28° to 36° Baumé gravity gas oil derived from petroleum. The apparatus as shown is designed to crack the vapors in the most efficient way, and then remove the heat from the cracked vapors in such a manner that the heat so removed will not be lost but taken up by oil that is to be vaporized and returned to the cracking zone. In this case the heat is removed in four successive stages, in such a manner as to cause the vapors to condense forming into four different products, one of these products being the finished gasoline-like material or related light oil,—the desired product for which the plant was designed,—another product being a heavy residuum, and the 75 two other products being a heavy and light gas

oil respectively which are used in the system to maintain the desired temperature on the incoming vapors, and as an absorbing oil to remove the very light gasoline-like material that is entrained in the gas from the separator drum.

Regarding the relation of the pressures in different parts of our apparatus, it may be stated that in actual practice we carry from 15 to 60 pounds pressure on our primary still 2a, from 12 to 14 pounds absolute pressure on the flashpot 1, and from 6 to 14 pounds pressure absolute on our cracking zone 2 and towers 6, 7, 8 and 11.

What we claim is:

1. The method of treating hydrocarbon oils to produce lower boiling hydrocarbons from higher boiling hydrocarbons which comprises the following steps: forcing charging oil under regulable pressure into a preheating zone, preheating the same therein to a temperature sufficient to flash the oil into vapor at sub-atmospheric pressure, while maintaining in said zone a pressure above atmospheric, releasing said oil from pressure in the preheating zone into an expanded flashing zone to flash into vapor substantially the entire amount of said oil while maintaining sub-atmospheric pressure, drawing only the vapors produced in the flashing zone through an open connection into a cracking zone which is under a lower sub-atmospheric pressure, drawing out the cracked vapors so as to maintain the said low pressure, passing them through fractionating zones, and passing the desired vapors from the last fractionating zone to cooling and separating zones.

2. The process described in claim 1 in which the charging oil is released from the preheating zone into the flashing zone under sub-atmospheric pressure while pumping on the outlet of the separating zone to maintain said subatmospheric pressure back through the cooling, fractionating, and cracking zones to the flashing zone.

3. The method of treating hydrocarbon oils to produce lower boiling hydrocarbons from higher boiling hydrocarbons which comprises the following steps, forcing charging oil into a preheating zone, preheating the same therein while maintaining in said zone a pressure above atmospheric, releasing said oil from pressure in the preheating zone into a flashing zone while maintaining therein subatmospheric pressure by drawing the vapors produced in the flashing zone through an open connection into a cracking zone under a lower subatmospheric pressure, drawing out the cracked vapors so as to maintain said low pressure, passing them through fractionating zones, passing the desired vapors from the last fractionating zone to cooling and separating zones, and after the system is on stream, reducing said initial charging oil, preheating make-up oil in the fractionating zones under pressure and thereafter releasing the make-up oil from pressure into the flashing zone.

4. The method of treating hydrocarbon oils to produce lower boiling hydrocarbons from higher boiling hydrocarbons which comprises the following steps, forcing charging oil into a preheating zone, preheating the same therein while maintaining in said zone a pressure above atmospheric, releasing said oil from pressure in the preheating zone into a flashing zone while maintaining therein subatmospheric pressure by drawing the vapors produced in the flashing zone through an open connection into a cracking zone under a lower subatmospheric pressure, drawing out the cracked vapors so as to maintain said

low pressure, passing them through fractionating zones, passing the desired vapors from the last fractionating zone to cooling and separating zones, the cracked vapors being passed through the fractionating zones in tandem and cooled therein in successive zones so as to throw down tar in the first zone, heavy gas oil in the second zone, and light gas oil in the third zone, pumping the heavy gas oil from the second to the first fractionating zone to soften and remove the tar therefrom, and pumping light gas oil from the third fractionating zone back through the fractionating zones in conductive relation to but out of contact with the vapors therein, to the flashing zone.

5. The method of treating hydrocarbon oils to produce lower boiling hydrocarbons from higher boiling hydrocarbons which comprises the following steps: forcing charging oil into a preheating zone, preheating the same therein while maintaining in said zone a pressure above atmospheric, releasing said oil from pressure in the preheating zone into a flashing zone while maintaining therein subatmospheric pressure by drawing the vapors produced in the flashing zone through an open connection into a cracking zone under a lower subatmospheric pressure, drawing out the cracked vapors so as to maintain said low pressure, passing them through fractionating zones, passing the desired vapors from the last fractionating zone to cooling and separating zones, the cracked vapors being passed through the fractionating zones in tandem and cooled therein in successive zones so as to throw down tar in the first zone, heavy gas oil in the second zone, and light gas oil in the third zone, pumping the heavy gas oil from the second to the first fractionating zone to soften and remove the tar therefrom, and pumping light gas oil from the third fractionating zone back through the frac-

tionating zones in conductive relation to but out of contact with the vapors therein, to the flashing zone, said reflux condensate from the third fractionating zone being exposed in successive fractionating zones by means of heat absorbing surfaces increasing successively in superficial area from the last to the first, whereby both the heating effect on the reflux oil and the cooling effect on the vapors under fractionation may be suitably adjusted.

6. The method of treating hydrocarbon oils to produce lower boiling hydrocarbons from higher boiling hydrocarbons which comprises the following steps: forcing charging oil into a preheating zone, preheating the same therein while maintaining in said zone a pressure above atmospheric, releasing said oil from pressure in the preheating zone into a flashing zone while maintaining therein subatmospheric pressure by drawing the vapors produced in the flashing zone through an open connection into a cracking zone under a lower subatmospheric pressure, drawing out the cracked vapors so as to maintain said low pressure, passing them through fractionating zones, passing the desired vapors from the last fractionating zone to cooling and separating zones, the cracked vapors being passed through the fractionating zones in tandem and cooled therein in successive steps so as to throw down condensate therein, pumping condensate from a fractionating zone back under pressure as reflux through the said fractionating zones in heat conductive relation to but out of contact with the vapors therein causing the same thereby to absorb heat from the cracked vapors, and finally passing the same into the flashing zone for re-treatment.
